BERT G. GOBLE, OF TULSA, OKLAHOMA, ASSIGNOR TO W. A. QUIGLEY

PUMPING-JACK MULTIPLIER, SWING, AND HOLD-UP

Application filed December 31, 1926. Serial No. 158,247.

This invention relates to an improved multiplier, swing and hold-up for shackle rod lines such as are used in the oil fields.

A very important object of this invention is to provide a curved path for the pulling element or chain to run in whereby the leverage point, relative to the pivot point, will be varied and keep the leverage point in the right position relative to the fulcrum.

Another object is to provide a multiplier which may be used as a hold-up, for instance, where the shackle line starts down a hill.

The multiplier may be used as a hold-up and thereby take the weight of the line off of the posts and to reduce or to increase the length of stroke and also may be used either in a horizontal or a vertical position.

Further objects and adjustments will become apparent as the description proceeds.

Fig. 1 is a side view of my vertical multiplier showing the curved casting 18 whereby the length of the leverage stroke is varied as well as its point of application. This figure also shows its adjustable hold-up.

Fig. 2 shows a cross sectional view on the line 2—2 of Fig. 1 showing the adjustable bearing used by the outgoing shackle rod.

Fig. 3 shows a view taken on line 3—3 of Fig. 1.

Fig. 4 shows an enlarged view of the top portion of the adjustable hold-up.

Fig. 5 shows a modification of my invention in which the main fulcrum for the cross member is pivoted to a vertical pivot.

Fig. 6 shows a view on line 6—6 of Fig. 5, showing the details of the spherical brace 41.

Fig. 7 is a modification of my invention wherein the pull is completely reversed.

Referring now in detail to the drawings, Fig. 1 shows a member 15 pivoted on a bearing 13. Braces 14 and 16 are rigidly connected with the member 15 as clearly shown in Fig. 1. An arm 17 protrudes out from brace 14 and has a series of holes by means of which the curved casting 18 is adjustably connected to it, the other end of this casting being supported by the brace 16.

Chain 26 is pivotally mounted to this casting 18 so that the chain abuts the curved surface of the casting as the entire frame is oscillated above its pivot 13. The other end of the chain is fastened to the shackle rod 20 by means of the clamp 21.

This incoming line from the power (not shown) is supported by means of a hold-up consisting of lower part 27' fastened to a casting 30, which forms a pivot point and an upper slide part 27, which is adjustably mounted on 27'.

As shown in Fig. 4, casting 28 is bolted to the upper part of 27, shackle rod 20 being firmly held in a clamp, this clamp being designated 29 as shown in Fig. 4. The out-going shackle rod 22 is fastened to a T-bearing 23 pivotally supported in bearing 24, said bearing being adjustably held on member 14 by bolts 25.

Fig. 2 shows the details of this connection.

Referring now to the modification shown in Figs. 5 and 6, 31 indicated a concrete foundation having the I-beam 40 rigidly embedded therein.

Bearings 34 are fastened to this I-beam. The main cross arm 32 has a journal 33 rigid therewith which oscillates in these bearings. Braces 35 and 36 are pivoted to arm 32 and have several holes at their outer ends, whereby the curved casting member 37 may be attached thereto in a number of different positions. This curved casting is further supported by means of adjustable pull brace 38.

Chain 26¹ is fastened to one end of the curved casting member by means of a shackle clamp 37A. The other end of the chain may be connected to the shackle rod line.

The main fulcrum member 32 has a series of holes wherein the bearing 39¹ may be adjustably mounted thereon.

As shown in Fig. 6 brace 41 has two spherical washers, 50, at its upper end, said washers fitting in correspondingly shaped recesses in either side of the casting 49, said casting being rigid with the post 40.

Referring now to Fig. 7, 47 indicates a concrete foundation in which the I-beam 46 is rigidly embedded.

A triangular shaped frame is composed of the main fulcrum member 42, braces 43 and 44, and curved casting 45 is adjustably mounted in any of the several holes at the

ends of these braces as clearly shown in Fig. 7. The usual chain 26² is fastened to casting 45. This triangular shaped frame is pivoted to the I-beam 46 by means of journal 33¹ and bearing 34¹. The out-going shackle line (not shown) is fastened to the T-bearing 23², which is held in the adjustable bearing 39².

I claim:—

1. A multiplier consisting of a bearing, a member pivoted thereon, braces fastened to the member and means on the braces for connecting them to pulling elements, said braces, member and means all being on one side, with reference to a vertical plane, of the bearing axis.
2. A multiplier as set forth in claim 1 but also having a counterweight fastened on the member, and the incoming pulling element arranged to act in the same direction about the said bearing as the counterweight.

In testimony whereof I affix my signature.

BERT G. GOBLE.
